UNITED STATES PATENT OFFICE.

LOUIS E. HASTINGS, OF MANNING, IOWA.

WAGON-TONGUE SUPPORT.

SPECIFICATION forming part of Letters Patent No. 349,714, dated September 28, 1886.

Application filed July 22, 1886. Serial No. 208,706. (No model.)

To all whom it may concern:

Be it known that I, LOUIS E. HASTINGS, a citizen of the United States, residing at Manning, in the county of Carroll and State of Iowa, have invented certain new and useful Improvements in Wagon-Tongue Supports; and I do hereby declare that the following is a full, clear, and exact description of the same, reference being had to the accompanying drawings, forming a part of this specification.

The object of my invention is to provide a simple and expeditious means of increasing or decreasing the tension of an elastic tongue-support while the tongue is supported thereby and without disconnecting the pole from the support; and it consists in the novel combination and arrangement of parts, hereinafter fully described, and specifically pointed out in the claims.

20 In the drawings, Figure 1 is a view taken transversely through the center of the forward axle, showing the wheel, one of the hounds, and a portion of the tongue and the improved devices for supporting the tongue. Fig. 2 is 25 a perspective view of the spring and the adjusting devices.

Upon the front axle, A, of a carriage requiring the service of a pole, are attached in the ordinary manner the hounds B, between 30 which hounds is secured by the bolt D, which passes transversely through the ends of the hounds, the tongue E. The width between the hound B B on the axle A is made sufficient to receive the end of a flexible forked end of a 35 tongue, and between said forked ends and to the bolt the adjusting devices may be attached.

Beneath the axle A, I arrange a semi-elliptic spring, F, one end of which bears upwardly against the under side of the axle, and 40 the opposite end is attached to a loop, g, on the end of an adjustable bolt, G. The bolt G is screw-threaded, and is inserted through the perforation e in the tongue E, and upon said bolt is fitted two nuts, one nut, g², bearing against the under side of the tongue E, by 45 means of which adjusting-nuts the bolt G may be raised or lowered sufficiently to accomplish its results, hereinafter specified.

Upon the under side of the spring F, and 50 through the box f, which is attached to said spring, I introduce a rod, H, and bend the op-

posite ends, h h, of said rod upwardly on either side of the spring F, and form a screw-thread on the said opposite ends, h h, of said rod H. I then make a nut, I, of increased 55 length, and from one end I make an interior right-hand screw-thread and from the opposite end a left-hand thread. The nuts I are then fitted on the ends h h of the bent rod H and turned a sufficient distance. The 60 left-hand screw-thread being upward in the nut, I then introduce the end k of a rod, K, which is also screw-threaded and fitted to the left-hand screw-thread of the nut, and upon the opposite side a similar rod, K, in the same 65 manner.

A slight distance above the screw-threaded ends h h of rod H, I rigidly cast the hooks k k', which hook over the transverse bolt D and sustain the weight of the spring F, and 70 from which point of support the power is distributed equally between the pole and axle. I make the rod of such a length that the extreme ends k², opposite to that having the screw-threads, may be bent into a hooked form, and when the pole is detached from the hounds the rod K may be supported by the said hooks, 75 thus keeping the spring from falling upon the ground.

For the purpose of increasing the tension of 80 the spring F, the nuts I are turned in one direction and the ends of the opposite rods are brought nearer together, thus elevating the pole sufficiently to relieve the weight from the team, and this is accomplished without the 85 necessity of unhitching the pole. Should the tension be required in greater degree, the nuts on bolt G are loosened and the nut g² turned so as to throw the bolt G in a downward direction, and with it the end of the spring F, attached thereto. The advantage is also gained 90 of being able to adjust the tension of the spring F without unhooking the supporting device.

Having fully described my invention, what I now claim as new, and desire to secure by 95 Letters Patent, is—

1. A wagon-tongue support consisting of a tongue arranged between suitable hounds on the axle of a vehicle, a spring attached at one end to the tongue and the opposite end to the 100 axle, and an adjustable supporting device attached midway the length of and to said spring,

and also to a suitable bolt on said hounds, and an adjusting-bolt on the end of said spring extending through said tongue, as and for the purpose specified.

5 2. The combination, in a wagon-tongue support, of the axle having hounds, a tongue between said hounds, and a supporting-bolt, of a spring having one end provided with an adjusting-bolt and nuts attached to the said tongue, to and the opposite end of said spring attached to

15 said axle, and rods provided at one end with right and left hand screw-threads attached to said spring and also to said supporting-rod, and intermediate adjusting-nuts provided with right and left hand screw-threads, as shown and described.

LOUIS E. HASTINGS.
